UNITED STATES PATENT OFFICE

113,781

DESIGN FOR A TEXTILE FABRIC

John R. Flather, Lowell, Mass., assignor to Boott
Mills, Lowell, Mass.

Application January 6, 1939, Serial No. 82,204

Term of patent 7 years

To all whom it may concern:

Be it known that I, John R. Flather, a citizen of the United States, residing at Lowell, in the county of Middlesex and State of Massachusetts, have invented a new, original, and ornamental Design for a Textile Fabric, of which the following is a specification, reference being had to the accompanying drawing, forming a part thereof.

In the drawing:

The figure of the drawing is a plan view of the fabric showing my design.

I claim:

The ornamental design for a textile fabric, as shown.

JOHN R. FLATHER.
